UNITED STATES PATENT OFFICE

LOUIS I. BECKWITH, OF DORCHESTER, MASSACHUSETTS

REFRIGERATING INSTALLATION

Application filed August 27, 1929. Serial No. 388,763.

This invention relates to refrigerating apparatus and more particularly to apparatus of the type in which the cooling unit is arranged either above, or in the upper portion 5 of the storage compartment.

In certain refrigerating installations such as the cold rooms employed for the storage of food stuffs in markets or the like, the cooling unit is often disposed above the storage 10 space to permit the effective circulation of air and to leave the maximum amount of room readily available for storage purposes. Installations of this character are ordinarily provided with bunkers or baffles which may 15 comprise inclined wall elements to aid the circulation of the air currents and to receive the moisture dripping from the cooling coils, or the like, thus protecting the stored articles.

Bunkers or baffles of this character are 20 commonly provided with body portions of heat non-conductive material, such as wood, cork, combinations of the same or the like, these materials ordinarily being sheathed with metal to permit the ready cleaning of 25 the bunkers and to prevent undue absorption of moisture by the body portion thereof. Ordinarily, moisture will tend to collect upon the cooling unit and adjoining parts of the installation due to the low temperature of the 30 same. Under the temperature conditions ordinarily employed, this moisture may form a layer of frost upon the cooling coils and the adjoining bunker or baffle pan, or relating parts of the installation. When the door 35 of the storage compartment or cold room is opened, the temperature of this frost may rise sufficiently to cause melting and dripping of the moisture while the incoming air introduces an additional quantity of moisture, the 40 major portion of which will in turn become deposited on the coldest part of the installation. Installations of this character prevent the direct falling of condensate from the cool- 45 ing unit upon the stored articles such as food stuffs. The temperature of the bunker pan itself has often been so low as to cause objectionable collection of moisture and formation of frost upon its lower surface which is 50 above the stored materials; this moisture has

thus caused objectionable dampness or wetting of the stored materials.

The present invention provides an arrangement which avoids this objection to refrigerating installations of this character. 55 To this end, the metal covering of the bunker and baffle wall is interrupted so that separate metal layers are arranged upon the side of the same adjoining the cooling unit and upon the side of the same adjoining the storage 60 compartment or region. Since the body portion of the bunker is formed of material which is a comparatively poor conductor of heat, a definite differential will exist between the temperatures of the metal sheets which are thus separated. Accordingly, the metal sheathing of the bunker which is directly above the storage space is at a temperature 65 appreciably higher than that in the region of the cooling unit, i. e. upon the upper surface of the bunker pan, and there is little tendency for moisture to collect upon surfaces from which it might fall upon the stored articles. Furthermore, this arrangement prevents the undesirable and unnecessary cooling of the under portion of the bunker pan, thus aiding the thermal efficiency of the apparatus and the desirable circulation of the air between the bottom of 70 the cold room and the cooling unit. 75

Further features of the invention relate to improved arrangements of the supporting structure of installations of this character, and particularly, to supporting elements which are adapted to withstand the comparatively adverse conditions to which they are subjected, and which may be readily assembled in practically any desired location. To this end, a plurality of expandable columns 80 are provided, suitable supporting brackets being associated therewith to receive beams or frame members which carry the cooling unit or the like.

These and other objects are effected by invention as will be apparent from the following description and claims taken in connection with the accompanying drawings, forming a part of this application, and in which:

Fig. 1 is an elevational view showing the 100 bunker arrangement of a refrigerating appa-

ratus, with some parts broken away and other parts shown in section;

Fig. 2 is a detail view showing in sectional elevation the manner in which the baffle and the floor pan are joined together;

Fig. 3 is a detail view showing the lower end of the floor pan and the drainage connection in sectional elevation;

Fig. 4 is a detail view showing the upper portion of the baffle of Fig. 1 in sectional elevation;

Fig. 5 is an enlarged detail showing in elevation with parts broken away, the manner in which the framework is supported from the main supports; and

Fig. 6 is a plan view of the foot used with the main supports shown in Figs. 1 and 5.

In accordance with a preferred embodiment of the present invention, means are provided for preventing the transfer of heat by conduction through the metal covering and around the edge portions of the walls, baffles and the like, which separate the cooling unit from the storage compartment. This is

accomplished conveniently by interrupting the metal covering along the edge portions of the walls or baffles so as to provide isolating spaces along the edges of the latter. By means of this construction it is possible to maintain a temperature at or below the dew point on the sides of these walls adjacent the cooling unit and thus to produce a sufficient cooling effect for maintaining the requisite temperature above the dew point on the opposite sides of these walls and throughout the storage compartment and hence, to provide adequate refrigeration without having condensation collect to any appreciable extent on the walls of the storage compartment.

The apparatus also includes a unitary bracket which is interposed between the juxtaposed ends of a sectional supporting member and held in place by stresses imposed upon the supporting member and also by flanges which are arranged to receive the adjacent ends of the supporting member. The flanges also assist in distributing stresses imposed upon the supporting arm of the bracket.

In Fig. 1 the cooling unit is indicated generally at 10 and is supported by a framework 11 which is carried by the main vertical supporting members 12. The pipes 13 of the cooling unit are supported upon transverse angles 14 and these angles are carried by hangers 16 suspended from upper transverse angles 17. The hangers 16 may be in the form of rods having threaded ends which are attached to the respective upper and lower transverse angles by means of nuts 18 which are provided with washers 19.

The outer end portions of the transverse angles 17 rest upon the top flanges of side angles 21 and are fixedly connected thereto in any approved manner as by means of bolts 22.

The angles 21 serve as the side members of the upper portion of this framework and are arranged to rest upon the arms 23 of brackets 24 carried by the vertical members 12.

The vertical supporting members or columns 12 preferably consist of tubular sections 26 and 27 (Fig. 5), which may be of different diameters, and have their ends in juxtaposed alignment. Bracket 24 is a unitary member which may be a casting and has a transverse web or flat portion 28 which is interposed between the adjacent portions of the tubular elements 26 and 27 and in abutting relation therewith. Upper and lower flanges 29 and 30 respectively, are provided on the web portion 28 for receiving the juxtaposed ends of the columnar sections 26 and 27. Extending outwardly from bracket 24 and preferably as a continuation of the web 28 is a supporting arm 31, which is reinforced by webs 32 that extend to the annular flange 30 of the body of the bracket. The frame members 21 have their upper flanges turned outwardly and disposed upon the arms 31 and connected thereto by means of bolts 33.

The upper section 26 of the vertical supporting member 12 is provided with threads 34 for receiving an attaching head 35. By effecting the proper vertical adjustment of the upper section 26, by means of the threads 34, with the head 35 it will be obvious that the latter may be forced against an upper wall or ceiling and thus effectively support the upper end of column 12. Openings 36 in the lower portion of member 26 may be engaged by a tool to permit rotation of this member and the proper adjustment of the length of the post or column 12.

An inclined bunker pan 39 is preferably disposed below the cooling unit being supported upon the inclined members 41, the ends of which are secured to the posts or columns 12. An upright baffle 38 is preferably mounted upon the upper end of the inclined pan 39 and cooperates therewith in aiding the natural circulation of the air above the cooling unit and the stored articles. The pan 39 is also adapted to catch condensate dropping from the cooling unit 10, being provided with a well or trough 42 and a drainage connection 43 to permit the ready emission of moisture thus collected.

The vertical baffle 38 and the pan 39 are provided with wooden frames 44 and 46 respectively, which support suitable insulating slabs 47, such as cork-board covered on both sides with a protective compound such as asphalt. The wooden frames 44 and 46 and the insulating material are then covered with sheets of metal 48. These sheets of metal are preferably arranged to be coextensive with the respective side walls of both the baffle 38 and the pan 39 and are also bent over the respective edge portions of these members so as to form flanges covering the adjacent margin.

nal portions of the edges, said flanges positioning the metal relatively to the frames. However, the edges of the flanges of the covering sheets are separated along the top, bottom, and vertical edges of the baffle 38 to provide an intervening space 29 (Fig. 4) for preventing the transfer of heat from one layer of metal to the other by direct conduction across the edge portions of the baffle. The flanges of the sheets forming the metal covering of the pan are also spaced from each other along the top outer edges of the side and end walls of the inclined pan 39 to provide an intervening space 51 (Fig. 1) for the purpose of preventing transfer of heat by conduction through the metal covering between the upper and lower sides of the pan.

Due to the provision of insulating spaces 49 and 51 at the edges of the baffle members 38 and 39, respectively, a definite temperature differential ordinarily exists between the opposite faces of these baffle members. Accordingly, the portions of the same from which condensate might fall upon the stored articles, are maintained at a temperature considerably higher than the minimum temperature within the cold room so that the circulating air tends to deposit its moisture upon other portions of the installation such as the cooling unit 10, and the upper face of pan 30, and there being little tendency for moisture to collect upon portions of the baffle from which it would drop upon the stored articles; as a result, objectionable wetting or dampness of these articles is avoided.

In apparatus of the type described, the connection currents pass upwardly at the right, as viewed in Fig. 1, then over the top of the baffle 38, about the cooling unit 10, and then downwardly past the lower end of the pan 39. The lower edge of the baffle 38 is provided with dowels 52 which are inserted in suitable recesses provided in the upper end wall of the pan 39 and thus provide for supporting the baffle 38 on the pan 39. The metal covering 48 for the baffle 38 is preferably arranged in the form of a lip 50 which depends within pan 39 so that condensation collecting on the baffle 38 will pass down along this lip into the pan, thus preventing condensed moisture from passing outwardly between the upper edge of the pan and the baffle 38.

I claim:

1. A refrigerating installation comprising a compartment having upper and lower imperforate walls of insulating material, expandable uprights extending between and fitting snugly against these upper and lower walls, upper and lower transverse members extending between the uprights and connected thereto to form a supporting framework, a cooling unit, means for supporting the cooling unit solely from the upper transverse members, a bunker pan disposed be-

neath the cooling unit and comprising insulating material disposed between outer layers of metal sheathing, means for supporting the bunker pan solely from the lower transverse members, the layers of metal sheathing being substantially continuous over the upper and lower surfaces of the bunker pan but being separated by a substantially continuous gap extending around the edges thereof to avoid transfer of heat by conduction through the metal sheathing from the upper to the lower surface of the bunker pan so that the upper surface of this pan may remain at a substantially lower temperature than the lower surface thereof, whereby articles stored below the pan may remain at a temperature definitely higher than that in the region on the upper side of the pan adjacent the cooling unit.

2. A refrigerating installation comprising a compartment having upper and lower imperforate walls of insulating material, expandable uprights extending between and fitting snugly against these upper and lower walls, upper and lower transverse members extending between the uprights and connected thereto to form a supporting framework, a cooling unit, means for supporting the cooling unit solely from the upper transverse members, a pan disposed beneath the cooling unit and comprising insulating material disposed between metal sheathing, the pan resting upon and being supported solely by the lower transverse members, the metal sheathing being substantially continuous over the upper and lower surfaces of the pan but being separated by a substantially continuous gap extending around the edges thereof to avoid transfer of heat by conduction through the metal sheathing from the upper to the lower surface of the pan, and an upright baffle member comprising insulating material between metal sheathing, the metal sheathing being folded substantially against itself along the lower edge of the baffle to form a depending lip, and means for supporting the baffle member on the pan with the depending lip disposed within the pan so that drippings from the baffle will fall within the pan.

3. A refrigerating installation comprising a compartment having upper and lower imperforate walls of insulating material, expandable uprights extending between and fitting snugly against these upper and lower walls, upper and lower transverse members extending between the uprights and connected thereto to form a supporting framework, a cooling unit, means for supporting the cooling unit solely from the upper transverse members, a pan disposed beneath the cooling unit and comprising insulating material disposed between metal sheathing, the pan resting upon and being supported solely by the lower transverse members, the metal sheath-

ing being substantially continuous over the upper and lower surfaces of the pan but being separated by a substantially continuous gap extending around the edges thereof to avoid transfer of heat by conduction through the metal sheathing from the upper to the lower surface of the pan, and an upright baffle member comprising insulating material between metal sheathing, the metal sheathing being folded substantially against itself along the lower edge of the baffle to form a depending lip, this lip being substantially in alignment with the side of the baffle adjacent the cooling unit, dowels spaced along the lower edge of the baffle outwardly of the depending lip, the pan having recesses registering with and receiving the dowels for removably supporting the baffle with the depending lip thereof disposed within the pan.

4. A refrigerating installation comprising a compartment having upper and lower imperforate walls of insulating material, expandible uprights extending between and fitting snugly against these upper and lower walls, upper and lower transverse members extending between the uprights and connected thereto to form a supporting framework, a cooling unit, means for supporting the cooling unit solely from the upper transverse members, a pan disposed beneath the cooling unit and comprising insulating material between metal sheathing, the pan resting upon and being supported solely by the lower transverse members, the metal sheathing being substantially continuous over the upper and lower surfaces of the pan but being separated to form a substantially continuous gap extending around the edges of the pan to avoid transfer of heat by conduction through the metal sheathing from the upper to the lower surface of the pan, an upright baffle member comprising insulating material between metal sheathing, this sheathing being separated along the upper and along the substantially vertical edges of the baffle to form a substantially continuous gap extending along these edges to avoid transfer of heat by conduction through the metal sheathing from one side to the other thereof, and means for removably supporting the baffle along an edge portion of the pan.

5. In a refrigerating installation, the combination of a drip pan comprising insulating material between metal sheathing, this sheathing being substantially continuous over the upper and lower surfaces of the pan and being separated along the edges thereof to avoid transfer of heat by conduction through the metal sheathing from the upper to the lower side of the pan, an upright baffle comprising insulating material between metal sheathing, this sheathing being substantially continuous over the sides of the baffle and being separated along the upper and sub-

stantially vertical edges thereof to form a substantially continuous gap along these edges for avoiding transfer of heat by conduction from one side of the baffle to the other, the metal sheathing being folded substantially upon itself along the lower edge of the baffle to form a depending lip substantially in alignment with one side of the baffle, and dowels on the lower edge of the baffle, the pan having recesses registering with and receiving these dowels, the recesses being located to support the baffle with the depending lip projecting within the pan so that drippings from the baffle may fall within the pan.

6. In a refrigerating installation of the type having a storage space and a cooling unit disposed above the storage space, the combination of a baffle member extending beneath the cooling unit and between the latter and the storage space, said baffle member comprising a body portion of insulating material and layers of imperforate metal sheathing covering said insulating material and forming the upper and lower surfaces of said baffle member, said layers of metal sheathing having positioning and protecting flanges engaging the edges of the body portion of the baffle member, the flanges of the respective layers of sheathing being so spaced that heat cannot be conducted directly from one layer of sheathing to the other, so that said layers are substantially out of direct heat conducting and heat transferring relation whereby the layer of sheathing adjoining the cooling unit may have a temperature which is definitely lower than that of the layer which is disposed above the storage space.

7. In a refrigerating installation of the type comprising a storage space and a cooling unit disposed above the storage space, the combination of a bunker pan directly beneath the cooling unit, an upright baffle adjoining the end of the bunker pan, layers of imperforate metal sheathing covering those sides of the bunker pan and baffle which are exposed to the cooling unit, other layers of imperforate metal sheathing covering the lower side of the bunker pan and the side of the baffle remote from the cooling unit, the several layers of metal sheathing having positioning flanges engaging edges of the bunker pan and edges of the baffle respectively, the edges of the flanges of said first mentioned layers of sheathing being spaced from the edges of the flanges of the other layers of sheathing, the layers of sheathing on the opposite sides of said pan and said baffle thereby being substantially out of direct heat conducting and heat transferring relation whereby the temperature of the metal sheathing from which condensate might drop upon articles in the storage compartment may be definitely higher than the temperature in the region of the cooling unit itself.

8. In a refrigerating installation of the type having a storage space and a cooling unit disposed above the storage space, the combination of a baffle member extending beneath the cooling unit and between the latter and the storage space, said baffle member having a body portion comprising relatively non-conducting frame members and insulating material between the frame members, separate layers of imperforate metal sheathing covering the upper and lower faces of the baffle member, said layers having flanges substantially covering the edges thereof to protect the same from moisture and to position the layers relative to the body portion, the layers of metal sheathing being substantially co-extensive across the body portion of the baffle member while the flanges of the respective layers of sheathing are spaced at the outer edges of the baffle member, so that the upper and lower layers of sheathing and their respective flanges are substantially out of direct heat conducting and heat transferring relation, whereby the temperature of the metal sheathing adjoining the cooling unit may be definitely lower than that of the metal sheathing which is disposed adjacent to the storage space.

Signed by me at Everett, Massachusetts,
this twenty-second day of August, 1929.
LOUIS I. BECKWITH.
